C. A. SABBAH

PRESSURE CONTROL APPARATUS

Filed July 21, 1926

Inventor:
Camille A. Sabbah

by *Alexander S. Jant*
His Attorney.

UNITED STATES PATENT OFFICE.

CAMILLE A. SABBAH, OF SCHENECTADY, NEW YORK, ASSIGNOR TO GENERAL ELECTRIC COMPANY, A CORPORATION OF NEW YORK.

PRESSURE-CONTROL APPARATUS.

Application filed July 21, 1926. Serial No. 124,074.

My invention relates to apparatus for producing or maintaining a predetermined vapor pressure within a vessel, and has for its principal object the provision of an improved apparatus wherein a pressure control device is arranged to be interconnected with the vessel through a valve which operates automatically to seal the entrance to the vessel when the control device is not operating.

10 In the past, various means have been provided for controlling the entrance to a vessel containing a vapor which is required to be maintained within predetermined pressure limits. Many of these means involve the

15 use of gears, springs or other mechanical elements and are incapable of automatically closing the entrance to vessel when the pressure control device ceases to function. In accordance with my invention, these difficulties are avoided by the provision of a liquid seal which is opened and closed in response to operation of the pressure control device.

My invention will be better understood from the following description when considered in connection with the accompanying drawing and its scope will be pointed out in the appended claims.

The drawing shows a pressure control apparatus wherein my invention has been embodied.

This apparatus comprises a pressure control means, shown as a pump 1, which is connected to a pipe 2 through a valve or sealing means comprising pipes 3, 4, 5 and 6 and a sealed chamber 7 which contains a liquid such as mercury or the like. The pipe 2 is connected to the vessel containing the vapor which is to have its pressure controlled. The vertical part of pipe 2 is at least 30 inches in length to prevent the mercury from getting into the vacuum chamber.

In explaining the operation of the apparatus, it will be assumed that gas is to be withdrawn from the vessel through the passageway formed by the pipes 2, 3 and 6. For this purpose, the pipe 6 is connected to the low pressure side of the pump 1 and the pipe 5 is connected to the pump 1 at a point intermediate between its low pressure side and its exhaust, this point being so chosen that the upper surfaces of the liquid in pipes 2 and 6 are maintained in their illustrated

positions when the pump 1 is operating. When the pump ceases to function, however, atmospheric pressure is applied to the surfaces of the liquid within the chamber 7 and within the pipe 6 and the liquid rises within the pipe 2 to a point at which the end of the pipe 3 is closed and the ingress of air or vapor through the pipe 2 to the vessel is prevented. The entrance to the vessel is thus sealed at all times when vapor is not being withdrawn from it and this result is effected without the use of mechanical devices likely to be unsatisfactory in their operation.

The embodiment of the invention illustrated and described herein has been selected for the purpose of clearly setting forth the principles involved. It will be apparent however, that the invention is susceptible of being modified to meet the different conditions encountered in its use and I therefore aim to cover by the appended claims all modifications within the true spirit and scope of my invention.

What I claim as new and desire to secure by Letters Patent of the United States, is:

1. The combination of vapor pressure control means provided with low and intermediate pressure openings, means forming a passageway interconnected with said control means through said low pressure opening, means forming a sealed chamber interconnected with said control means through said intermediate pressure opening, and means interposed between said chamber and said passageway for causing said passageway to be closed in response to a predetermined change in the relation between the pressures at said low and intermediate pressure openings.

2. The combination of vapor pressure control means provided with low and intermediate pressure openings, means forming a passageway interconnected with said control means through said low pressure opening, means forming a sealed chamber interconnected with said control means through said intermediate pressure opening, a liquid within said chamber, and a pipe extending between said liquid and said passageway whereby said liquid is caused to close said passageway in response to a predetermined

change in the relation between the pressures at said low and intermediate pressure openings.

3. The combination of a pump provided with an inlet and outlet, means forming a passageway interconnected with said pump through said inlet, means forming a sealed chamber interconnected with said pump at

a point intermediate said inlet and outlet, and means interposed between said chamber and said passageway for causing said passageway to be closed when said pump ceases to function.

In witness whereof, I have hereunto set my hand this 20th day of July, 1926.

CAMILLE A. SABBAH.
